UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

METHOD OF MANUFACTURING DRAFT YOKES.

Application filed July 17, 1922. Serial No. 575,676.

To all whom it may concern:

Be it known that I, BYERS W. KADEL, a citizen of the United States, residing at Baltimore, in the State of Maryland, have 5 invented certain new and useful Improvements in Methods of Manufacturing Draft Yokes; and I do hereby declare the following to be a full, clear, and exact description of the invention, such as will enable others skilled in the art to which it appertains to 10 make and use the same.

My invention relates to a method of manufacturing draft yokes for railway cars. The object of the invention is to provide 15 a simple and practical process resulting in the production of a strong and reliable yoke constructed of wrought metal.

In the accompanying drawings, by which the steps in the method of manufacturing a 20 draft yoke are illustrated,

Figure 1 is a perspective view of a slotted blank formed as an endless band or ring, dot and dash lines indicating the positions assumed by the divided portions of the band 25 after they have been spread apart.

Figure 2 is a perspective view illustrating the stage of manufacture at which the intermediate parts of the divided segments of the band have been forced toward each 30 other subsequent to the outward bending of the divided segments.

Figure 3 is a side elevation, parts of the draft arms being broken away, showing the yoke after the divided segments have been 35 twisted to form spaced means adapted to cooperate with a coupler key and after the remaining portion of the band has been shaped to form the arms and rear end of the yoke.

40 Figure 4 is a plan view of the yoke construction shown in Fig. 3.

Figure 5 is a side elevation of the preferred form of the forward end of the completed draft yoke.

45 Figure 6 is a plan view of the forward end of the preferred form of the completed yoke.

In order to obtain all the advantages of 50 my invention, the metal blank from which the draft yoke is fashioned is in the form of a ring or endless band 1 which is preferably of rectangular cross section and of suitable proportions. This blank may be produced in any convenient manner, as for 55 example, by starting with an ingot, and forming a bloom which is then pierced and

rolled into ring shape after the manner commonly practiced in the manufacture of steel tires for locomotive driving wheels.

A portion of the endless band blank is 60 cut or slotted peripherally, as indicated at 2, to form divided segmental portions 3 which are integrally united at their opposite ends. The portions thus divided are then bent outwardly or forced apart, as 65 indicated in dot and dash lines in Fig. 1, and intermediate parts of the divided segments are thereafter preferably forced toward each other, as indicated at 4 in Fig. 2. These intermediate or central portions 70 of the segments 3 are adapted, in the completed yoke, to engage the well known key for connecting a coupler thereto. The divided segmental portions thus shaped are then twisted in opposite directions until 75 they assume the position illustrated in Figs. 3 and 4, and the remaining or unslotted portion of the endless band is shaped to constitute the arms 5 and rear end 6 of the device.

The heretofore described steps of the 80 method of manufacture produce in themselves a complete draft yoke of the form illustrated in Figs. 3 and 4, and where a yoke of that type is to be constructed no 85 further steps need be performed. But, as is preferred, when the hooded type of draft yoke is to be produced, metal pieces or insets 7, forming in conjunction with the neighboring portions of the yoke the side 90 walls of the hooded end thereof, are welded in place between the yoke arms, the welded union of said parts 7 with the portions of the yoke formed from the divided segments 3 being indicated in Fig. 5 by dot and dash lines 8. The upper and lower walls of the hooded portion of the yoke are similarly produced by welding in place oppositely disposed pieces 9 which extend between and unite the laterally spaced parts 3 of the device adjacent the forward ends of the arms 5, the line of welded union of said insets 9 with the portion of the yoke formed from the endless band being indicated in Fig. 6 by the dot and dash lines 10.

The reinforcing pieces 7 provide connections between the arms 5 of the yoke adapted to extend behind the usual coupler key; and for the purpose of receiving said key each of said parts 7 is suitably slotted, as 110 indicated at 11.

As will be appreciated, the construction

is such that the welds in all instances are subject only to compressive strains, while all the material of the yoke subjected to pulling forces is integrally united.

5. I claim:—

1. The method of manufacturing draft yokes which involves forming an endless metal band, slitting an intermediate segment of said band to form portions which 10 are integrally united at their opposite ends, and shaping said portions divided by slitting to form spaced means adapted to receive a coupler key.

2. The method of manufacturing draft yokes which involves forming an endless band, peripherally dividing a segment of said band, bending said divided portions outwardly, forcing intermediate parts of said divided portions toward each other, and 20 twisting said divided portions to form coupler key receiving means.

3. The method of manufacturing draft yokes which involves forming an endless band, peripherally dividing a portion of 25 said band, and subsequently shaping said divided portions to form spaced means adapted to receive a coupler key.

4. The method of manufacturing draft yokes which involves forming an endless 30 band, peripherally dividing a segment of said band, shaping said divided portions to form spaced means adapted to receive a coupler key, and shaping the remaining portion of said band to form the arms and rear 35 end of the yoke.

5. The method of manufacturing draft

yokes which involves forming an endless metal band, peripherally dividing a segment of said band, shaping said divided portions to form spaced parts adapted to 40 cooperate with a coupler key, shaping the remaining portion of said band to form the arms and rear end of the yoke, and welding in place oppositely disposed pieces tying said arms together and adapted to extend 45 behind the coupler key.

6. The method of manufacturing draft yokes which involves forming an endless metal band, peripherally dividing a segment 50 of said band, shaping said divided portions to form spaced parts adapted to extend around the forward edge of a coupler key, shaping the remaining portion of said band to form the arms and rear end of the yoke, forming a plurality of pieces respectively 55 adapted to fit within the spaced parts, and finally welding to the respective spaced parts said corresponding pieces.

7. The method of manufacturing draft yokes which involves forming an endless 60 metal band, peripherally dividing a segment of said band, shaping said divided portions to form spaced parts adapted to cooperate with a coupler key, shaping the remaining portion of said band to form the 65 arms and rear end of the yoke, and welding in place oppositely disposed pieces extending between and uniting said spaced parts adjacent the forward ends of the arms of the yoke.

In testimony whereof I affix my signature.
BYERS W. KADEL.
